CLAIM

The ornamental design for an interior control panel of motor vehicle as shown and described.

DESCRIPTION

FIG. 1 is a perspective view of an interior control panel of motor vehicle according to a first embodiment showing my new design;

FIG. 2 is a rear view thereof;

FIG. 3 is a front view thereof;

FIG. 4 is a right view thereof;

FIG. 5 is a left view thereof;

FIG. 6 is a top view thereof; and

FIG. 7 is a bottom view thereof.

FIG. 8 is a perspective view of an interior control panel of motor vehicle according to a second embodiment showing my new design;

FIG. 9 is a rear view thereof;

FIG. 10 is a front view thereof;

FIG. 11 is a right view thereof;

FIG. 12 is a left view thereof;

FIG. 13 is a top view thereof; and,

FIG. 14 is a bottom view thereof.
